[57] CLAIM

The ornamental design of a sporting equipment holder and organizer, as shown and described.

DESCRIPTION

FIG. 1 is a perspective view of a sporting equipment holder and organizer showing my new design. The broken lines showing a bat and rollerblade skates are for illustrative purposes only and form no part of the claimed design;

FIG. 2 shows a top plan view thereof;

FIG. 3 shows a front elevational view thereof;

FIG. 4 shows a right side elevational view thereof; (the left side elevation view is a mirror image of FIG. 4);

FIG. 5 shows a bottom plan view thereof; and,

FIG. 6 shows a rear elevational view thereof.
